INVENTOR

Alvin Foster,

BY

James J. Sheehy & Co.,

ATTORNEYS.

UNITED STATES PATENT OFFICE.

ALVIN FOSTER, OF NEW ORLEANS, LOUISIANA.

HANDLE.

1,411,209:

Specification of Letters Patent. Patented Mar. 28, 1922.

Application filed March 11, 1921. Serial No. 451,468.

To all whom it may concern:

Be it known that I, ALVIN FOSTER, a citizen of the United States, residing at New Orleans, in the parish of Orleans and State of Louisiana, have invented new and useful Improvements in Handles, of which the following is a specification.

My present invention pertains to handles, such for instance as are employed in connection with portable electric lamps of the type that are generally used by automobile mechanics and the like, and it contemplates the provision of a handle that is inexpensive to produce, and is, at the same time indestructible and acts as an insulator for the wires of the lamp.

The invention further contemplates a handle for the purpose set forth, formed of such material that liability of burning the hands of the user is removed and at the same time the material permits of perfect insulation and moreover, prevents the possibility of electric shocks from a shortened or ground wire or wires.

The invention, in all of its details, will be fully understood from the following description and claim when the same are read in connection with the drawings, accompanying and forming part of this specification, in which:

The figure represents my novel lamp handle partly in section and partly in elevation with the lamp socket arranged therein.

My novel handle comprises a section of pipe or metal section tubing 3 that is threaded at one end as indicated by 2 and this provision is made in order that the well socket 1 may be secured on the tubing.

As will be noted, the socket 1 is covered with insulating material 6 and the tubing 3 is covered with an insulating material 5 and said material may be either common

hose or a combination of flexible rubber and fabric and in this connection, I would have 45 it understood that the insulation extends from the upper end of the socket 1 to the lower end of the tubing 5.

As will be noted from the drawing, the lower end of the tubing 3 is beveled as indicated by 4 and hence injury to electric wiring that passes from the source of electric energy through the tubing and to the socket is inhibited.

It will be gathered from the foregoing 55 that the invention is simple and inexpensive in construction and highly efficient for the purpose for which it is intended.

I would distinctly have it understood that the fabric of which the insulation is formed 60 may be of any quality compatible with its purpose, and I would also have it understood that the handle may be employed in connection with various forms of electrical appliances.

Having described my invention, what I claim and desire to secure by Letters-Patent is:

In a device for the purpose set forth, the combination of an interiorly bored pipe section that is interiorly beveled from a point slightly above one end thereof to said end, interior threads formed at the opposite end of the section, and a covering of suitable material surrounding the section and extending above the upper end of the section to surround a lamp socket when threaded in the pipe section.

In testimony whereof I have hereunto set my hand in presence of two subscribing witnesses.

ALVIN FOSTER.

Witnesses:

M. E. KNIGHT,
CARL A. CONRAD.
